UNITED STATES PATENT OFFICE.

AARON S. NICHOLS, OF NEW YORK, N. Y.

HOLDER FOR DISK RECORDS.

1,026,111.

Specification of Letters Patent.

Patented May 14, 1912.

Application filed January 22, 1912. Serial No. 672,572.

To all whom it may concern:

Be it known that I, AARON S. NICHOLS, a citizen of the United States, residing in New York, in the county of New York and State of New York, have invented a new and useful Improvement in Holders for Disk Records, of which the following is a specification.

This invention is intended to serve as a receptacle for the storing of disk records used in phonograph and other talking machines.

My object in the invention has been to devise an inexpensive construction in which the disks can be safely kept very compactly, and without danger of mutilation or injury or rubbing of their record surfaces.

The invention is fully set forth below, and will be readily understood from the accompanying drawing when considered in connection with the following description.

In the drawing, Figure 1 is a front elevation of the invention. Fig. 2 is a transverse, vertical section. Fig. 3 is a partial, transverse section, taken through one of the spring disk holders, and Fig. 4 is a detail section across one of the holders.

In said drawing, 5 represents a suitable case, preferably open at the front side and closed upon the other sides. In this case are a series of vertical partitions 6 which may be of the form and dimensions shown in Fig. 2. They divide the interior of the case into individual disk spaces, each adapted to hold only a single disk. The disks which are shown at 7 are supported upon the inclined surface of a block 8 at the back of the case from which they will roll off automatically when released by the spring keys or holders 9, which are located along the front of the case and as shown are all preferably pivoted upon a rod 10 extending from end to end of the case. These keys or holders are all provided with springs 11 encircling their axial shaft, and tending to maintain them in the position shown at Fig. 3, each of the holders serving to retain one of the disks when in acting position. They can, however, be depressed from the position of Fig. 3 to the dotted position at the bottom of Fig. 2, and when so depressed, the disk confined by them will roll out in front where it can be readily taken hold of by hand. The springs upon the keys return them to normal position after they have been depressed in releasing

their disks. For thus depressing the holders, I place upon each of them a button 12, made large enough preferably to enable a numeral to be placed upon it and to serve as a guide in finding the disk when wanted. These buttons are arranged alternately in different planes, one series above the other, so that no confusion is likely to occur in releasing the disks. These keys or holders being thus numbered, enable the operator to take from the case any disk desired by first ascertaining the number assigned to that disk.

As a guard to prevent the pushing down of more than one key at a time, I sometimes place under the keys a cord extending from one end of the case to the other, and provide such cord with a knot 13 at one end adapted to prevent its being drawn through the case, and provide the other end with an excess length, so that such other end can be drawn into the case whenever any key is depressed, as shown in the dotted lines in Fig. 2.

In my improved disk holder, one of the essential features consists in supporting the disks at points which are slightly to the rear of the centers of gravity of the disks when the disks are within the case, so that when the inner end of the keys or retainers are depressed to a point below the supporting point for the disks, each disk will roll outwardly and forwardly, and during this operation the upper face of each key or retainer will serve to support the disk during a portion of its outward movement.

I have shown one form of my invention, but it will be understood that the same is merely illustrative and that various changes and modifications may be made, and all such changes and modifications are contemplated as fall within the scope of the appended claims.

I claim:

1. A holder for record disks for talking machines, comprising a suitable case having vertical partitions dividing it into disk spaces, and means for supporting and retaining the disks in place, comprising a plurality of spring controlled keys independently operable and each adapted to engage a disk on its front edge at a point above the lowest point on the periphery and retain it within the case against the force of gravity, one end of each of said keys being depressible to a position below the lowest point on

the periphery of the disk, whereby the disk will roll outwardly from the case by gravity upon the key being depressed, and said key will automatically return when released to 5 its original position after the disk has rolled out.

2. A holder for disks comprising, in combination, a suitable case having an open front and having also partitions dividing it 10 into disk spaces, means located in the rear of the case and adapted to support the disks in position above the bottom of the case, a plurality of pivoted keys or retainers, one for each disk, and each adapted to engage a 15 disk at a point above the lowest portion of the disk and in front of the point where the disk is engaged by the disk supporting means and retain it in the position within the case, said keys being independently movable and 20 each provided with a spring for normally throwing its inner end upwardly and means for limiting the upward movement of the inner ends of the keys, the inner end of each key being adapted to be depressed to release 25 a disk whereby the latter will roll outwardly from its support by gravity.

3. A holder for disks comprising, in combination, a suitable case having an open front and having also partitions dividing it 30 into disk spaces, means located in the rear of the case and adapted to support the disks in position above the bottom of the case, a plurality of pivoted keys or retainers, one for each disk, and each adapted to engage a 35 disk at a point above the lowest portion of the disk and in front of the point where the disk is engaged by the disk supporting means and retain it in the position within the case, said keys being independently movable and each provided with a spring for 40 normally throwing its inner end upwardly and means for limiting the upward movement of the inner ends of the keys, the inner end of each key being adapted to be depressed to release a disk whereby the latter will roll outwardly from its support by 45 gravity, each of said keys comprising a U-shaped metal member.

4. A holder for disks comprising, in combination, a suitable case having an open 50 front and having also partitions dividing it

into disk spaces, means located in the rear of the case and adapted to support the disks in position above the bottom of the case, a plurality of pivoted keys or retainers, one 55 for each disk, and each adapted to engage a disk at a point above the lowest portion of the disk and in front of the point where the disk is engaged by the disk supporting means and retain it in the position within 60 the case, said keys being independently movable and each provided with a spring for normally throwing its inner end upwardly and means for limiting the upward movement of the inner ends of the keys, the inner 65 end of each key being adapted to be depressed to release a disk whereby the latter will roll outwardly from its support by gravity, each of said keys comprising a U-shaped metal member, and when depressed 70 serving as a support for the disk as the same rolls outwardly.

5. A holder for disks comprising, in combination, a suitable case having an open 75 front and having also partitions dividing it into disk spaces, means located in the rear of the case and adapted to support the disks in position above the bottom of the case, a plurality of pivoted keys or retainers, one 80 for each disk, and each adapted to engage a disk at a point above the lowest portion of the disk and in front of the point where the disk is engaged by the disk supporting means and retain it in the position within the case, said keys being independently movable and each provided with a spring for 85 normally throwing its inner end upwardly and means for limiting the upward movement of the inner ends of the keys, the inner end of each key being adapted to be depressed to release a disk whereby the latter will roll outwardly from its support by 90 gravity, and a flexible member extending across the case and adapted to be engaged by each of the keys when moved from its 95 normal position, said flexible member having an excess length sufficient to allow the operation of one key at a time.

AARON S. NICHOLS.
